(57) **CLAIM**

The ornamental design for a shoe with illuminable heel light sequence, as shown and described.

DESCRIPTION

FIG. 1 is a first image in a sequence of a rear view of a shoe with illuminable heel light sequence showing our new design;

FIG. 2 is the second image thereof;
FIG. 3 is the third image thereof;
FIG. 4 is the fourth image thereof;
FIG. 5 is the fifth image thereof;
FIG. 6 is the sixth image thereof;
FIG. 7 is the seventh image thereof;
FIG. 8 is the eighth image thereof;
FIG. 9 is the ninth image thereof;
FIG. 10 is the tenth image thereof;
FIG. 11 is the eleventh image thereof;
FIG. 12 is the twelfth image thereof;
FIG. 13 is the thirteenth image thereof;
FIG. 14 is the fourteenth image thereof;
FIG. 15 is the fifteenth image thereof;
FIG. 16 is the sixteenth image thereof;
FIG. 17 is the seventeenth image thereof;
FIG. 18 is the eighteenth image thereof;
FIG. 19 is the nineteenth image thereof;
FIG. 20 is the twentieth image thereof;
FIG. 21 is the twenty-first image thereof;
FIG. 22 is the twenty-second image thereof;
FIG. 23 is the twenty-third image thereof;
FIG. 24 is the twenty-fourth image thereof;
FIG. 25 is the twenty-fifth image thereof;
FIG. 26 is the twenty-sixth image thereof;
FIG. 27 is the twenty-seventh image thereof;
FIG. 28 is the twenty-eighth image thereof;
FIG. 29 is the twenty-ninth image thereof; and,
FIG. 30 is the thirtieth image thereof.

The appearance of the shoe with illuminable heel light sequence sequentially transitions between the images shown in FIGS. 1-30. The process or period in which one image transitions to another forms no part of the claimed design. The heel display surface allows light to transmit therethrough. The broken line showing the remainder of the shoe is for environmental purposes only and forms no part of the claimed design.
